UNITED STATES PATENT OFFICE

BERNHARD SCHNEIDER, OF EICHWALDE, NEAR BERLIN, GERMANY

LIGHT REFLECTOR

Application filed October 24, 1929, Serial No. 402,273, and in Germany August 22, 1929.

This invention relates to a reflector with external or internal mirroring and having at its lower edge which is obliquely disposed to its axis, a cover plate which extends from 5 its shorter side and is adapted to disperse the light in diffuse fashion. In contradistinction to the known constructions of reflectors of this kind in which the cover plate consists of a separate piece fixed to the reflector, according to the present invention, the said light dispersing plate is made integrally with the reflector from one and the same piece of glass or other translucent material. Owing to the cover plate and the 15 reflector being made of one single piece of glass there results a form of construction which is suitable for mass production and which, moreover, permits the cover plate to be completely utilized for giving out light, 20 since the use of metal parts, such as are necessary for connecting a separate screen to a reflector of the kind referred to, is entirely avoided. Such metal parts increase the costs of production and darken the edge of the 25 screen surface with which they are employed. As the introduction of the incandescent lamp from the underside of the reflector is not interfered with by the partial covering over of said underside, it is possible to make the 30 upper edge of the reflector and the shade holder which engages the same narrower than when the lamp is introduced from the top, so that the loss of light through the opening at the top edge is reduced. The reflector is pro- 35 vided either internally or externally with a metallic coating and both the reflector and the cover plate, instead of being made of glass, may be constructed of some similar material, such, for instance as porcelain.

40 A further important feature of the invention consists in arranging the light dispersing plate to cover so much of the underside of the reflector and extending the reflector wall opposite said cover plate so far downwards 45 that in every aspect of the reflector in which the axis thereof remains vertical the source of light is practically invisible. As a result of this arrangement it becomes possible to use the reflector either with the longer side 50 wall or with the shorter one turned towards

the spectator without his being dazzled, since only diffusely dispersed light is permitted by the cover plate to reach his eyes. This possibility of using both sides allows the reflector, instead of being located between 55 the spectator and the space to be illuminated, to be arranged at the rearward end of this space or to be used at the same time for lighting up the space close to the spectator. Owing to its freedom from dazzling the reflector can also be disposed in a position intermediate between that in which the longer side wall is turned to the observer and that in which the shorter side wall is so turned, so 60 that freedom of choice as to the place where it is set up is still further enlarged. At the same time an effective and powerful concentration of light on to the desired place, without dazzling, is ensured for all settings of the reflector. 70

The invention will be more fully described by reference to the accompanying drawing showing by way of exemplification an embodiment of the principle of this invention. In the drawing Figures 1 and 2 illustrate re- 75 spectively in sectional view and in front elevation a form of construction in which the reflector and the covering disc constitute one single piece of glass.

The reflector 1 of glass in accordance with 80 the exemplification of Figures 1 and 2 of the drawing partially surrounds the electric incandescent lamp 2 which is retained at the upper edge of the reflector by means of a yoke or a cup holder 3 at the outside of which the 85 means for suspending or retaining the reflector, such as for instance a cord, a bolt, hook or the like are suitably disposed. One side of the wall of the reflector extends consider- 90 ably more downwards than the other portion of the wall, so that the lower edge of the reflector is situated in a plane at an angle to the axis of the device. A portion of the bottom part of the reflector is closed by an translucent or transparent disc or plate 4 95 which extends from the shorter side of the wall of the reflector and is made in one piece therewith and preferably covers up about half or even a somewhat larger portion of the lower open side of the reflector. The 100

lower edge 5 of the disc or plate 4 may be straight or curved. At its outside the reflector 1 is provided with a coating of deposited silver 6, while the outside of the disc 5 4 is ground, dimmed, fluted or roughened so that the light on passing through this plate will be diffused and dispersed. The reflected light is caused to pass to the outside through the lower opening 7 of the reflector and may be directed to the particular part of the space to be illuminated by correspondingly adjusting the position of the reflector. Inasmuch as the plate 4 will only allow diffused light to pass no dazzling action can occur even in case the short side of the wall of the reflector is made to face the observer, and it becomes possible by this means to also light up the space around the observer. In every position of the reflector a very intense illumination of the particular zone to be irradiated is accomplished and without any danger of dazzling action, and the reflector becomes, therefore, likewise adapted for the purpose of producing illumination by diffused light.

25 I claim:—

A combined light reflector and diffuser having a reflecting shell forming a truncated ovoid with a single plane of truncation at substantially 45° to the major axis of the shell and intersecting said axis adjacent the center thereof, and a diffusing plate extending along the plane of truncation from the short side of the shell to the said major axis and terminating in an edge at right angles to said major axis.

In testimony whereof I affix my signature.

BERNHARD SCHNEIDER.
